(57) CLAIM

The ornamental design for a ring mouse, as shown and described.

DESCRIPTION

FIG. 1 is a front, left and top perspective view of a ring mouse, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of area "9" in FIG. 1.

The broken lines shown in the drawings illustrate portions of the ring mouse that form no part of the claimed design.
